EASY CHAIR

Jean Prevost, 18 Bis Rue Danielle Casanova,
94 Le Perreux, France

Filed July 19, 1972, Ser. No. 273,188

Claims priority, application France Feb. 4, 1972

Term of patent 7 years

Int. Cl. D6—01

U.S. Cl. D6—67

FIG. 1

FIG. 2

FIG. 3

FIG. 1 is a perspective view of an easy chair embodying my new design;

FIG. 2 is a side view of the easy chair shown in FIG. 1; and

FIG. 3 is a rear view of the easy chair shown in FIGS. 1 and 2.

The other not shown side of the easy chair is identical with the side shown in FIG. 1.

I claim:

The ornamental design for an easy chair, as shown and described.
